UNITED STATES PATENT OFFICE.

HEINRICH GRÜNEWALD, OF HILCHENBACH, GERMANY.

ANNEALING FURNACE.

Application filed February 7, 1925. Serial No. 7,626.

To all whom it may concern:

Be it known that I, HEINRICH GRÜNEWALD, a citizen of the Republic of Germany, residing at Hilchenbach, Westphalia, Germany, have invented new and useful Improvements in Annealing Furnaces, of which the following is a specification.

My invention relates to annealing furnaces and more particularly to furnaces for removing scale, oxide, etc., from hoop iron, wire, plate and other metal objects.

Such articles were heretofore generally treated in pots the cavities of which were filled with gray cast iron chips. This method is expensive and involves loss of time due to the frequent filling and refilling of the pots.

It has been proposed to improve this method by performing it in an atmosphere separate from the atmospheric air or in an inert gas. Such furnaces, however, are complicated, involve high initial cost and the danger of explosion in case of failure of their complicated mechanism.

I have found that it is possible to remove scale, etc., from commercial iron, hoop iron, wire, plate and all other metals without inserting chips of gray cast iron or introducing inert gas. It is sufficient to close the furnace air-tight and to heat it to the desired temperature at which it is kept for the time required.

In order to enable the closure to exclude air with reliability during the functioning of the furnace, it should be remote from the heated zone. This is effected according to my invention by arranging the closure for the vessels containing the charge, which may be the retorts or a pot inserted therein, at the top of the furnace.

Retorts adapted to receive the charge or the pots extend to the upper end of the furnace where they are closed by a gas-tight cover. The brick work tightly hugs the retorts in its upper portion and below the upper end of the furnace.

By this arrangement, excessive heating of the cover and deterioration of the closure is prevented without interfering with the draught.

It has been found that the temperature of the cover is 200 to 300 centigrade so that there is no danger of damage to the closure.

If such damage does occur during operation due to any unfavourable circumstances, it 55 may be remedied by setting the screws of the packing more tightly.

Suitable cooling of the charge is equally important as heating. The charge is cooled by removing the retort from the furnace 60 after it has been heated for the required period. In order to facilitate the handling of the retort and to utilize the heat of the furnace properly, the annealing chamber and the retort are secured to a movable plate 65 which is carried on a pillar at its centre and on a circular track at its perimeter, the pressure on the track being distributed by rollers. The circular track at the same time serves to close the furnace. In this manner, the annealing chamber which comprises the flues for the furnace gases, is made movable together with the retort. The heat of the gases is utilized to the full extent, the gases flowing through each of the annealing chambers in the prescribed direction and giving up their heat.

During the heating of the retorts, the furnace should be in the most favourable position with regard to them and secondary air passages, etc., should be avoided. To this end, the furnace chamber is adapted to be adjusted horizontally and vertically so as to enable it to be adapted to the existing conditions of operation. During the heating 85 period, the furnace chamber is adjacent the base of the annealing chamber so as to provide a single combustion and flue chamber in which the heat of the gases is fully utilized.

Reference is to be had to the accompanying drawings in which my improved furnace is illustrated by way of example.

Fig. 1 is a longitudinal section of a furnace equipped with a furnace chamber adapted to be raised and lowered,

Fig. 2 is a plan view of the furnace.

A rotatable cover plate *a* is supported on a pillar *c* by a thrust ball bearing *b* at its centre. Its perimeter is carried on rollers *e* running on a circular track *d*, said rollers being kept apart by a cage *f*. The cage engages grooves *g* and *g'* of the track and cover plate *a*, respectively; and serves for preventing loss of heat from the annealing chamber flue *h*.

The cover plate *a* with the annealing

chambers, the retorts and annealing pots, may be rotated by any suitable means, not shown.

The annealing chambers are suspended 5 from the plate *a* and the retorts *k* are secured in suitable holes in the plate *a*.

The retorts *k* which may be of any suitable shape, of circular or rectangular section, as required by the goods to be treated, 10 are equipped with pots *l* in which the charge is placed on a table *m* to facilitate inserting and withdrawing. The pot *l* is closed at the top by a cover *n*. To prevent heating of the sealing faces, a passage *o* may be 15 formed in the cover *n* in which cooling water is circulated.

Two tubes *p* and *q* are secured in each cover *n*, the tube *p* being closed at the bottom and open at the top and serving for 20 inserting a pyrometer so that the temperature of the charge can be measured without allowing air to enter the pot *l*. The tube *q* which is open at both ends is equipped with a safety valve, not shown, in order to allow 25 vapours of oil or steam to escape which may form from grease or moisture adhering to the goods.

The operation of the furnace is as follows: Suppose all four chambers 1, 2, 3 and 4 as 30 shown in the plan view, to be charged. That chamber which is above the furnace *r*—or a gas or oil burner, as the case may be, is heated until the desired temperature, say 770 to 800 centigrade, has been attained. Now, the furnace chamber *r* is lowered by any suitable means, for instance a screw *u*, a bevel gear *t*, a shaft *s* and a handwheel *v*, or the gas or oil burner not shown, is withdrawn so as to enable the chamber *i* to be 40 revolved with the cover plate *a* until the next chamber is above the furnace chamber *r* which is now raised until its flange *w* engages a corresponding flange *x* at the bottom of the chamber *i*. In the case of an oil or 45 gas-fired furnace, the burner is replaced. The chamber *i* which is now above the furnace *r* has been previously heated to 500 to 600 centigrade by the waste gases from the furnace which circulate around those chambers, for instance 2, 3, and 4, which are not 50 being heated by the furnace chamber *r*, or the burner at the time. To this end, the chambers *i* are connected by flues *y'*, *y''*, *y³*, and *y⁴* and that chamber which is opposite the chamber being heated, in the present instance 3, is connected to a flue *z* in the brickwork of the furnace which conducts the waste gases to a chimney, not shown.

The chamber *i* is now heated to the desired temperature and maintained at that for 1 to 2 hours, whereupon the plate *a* is again rotated so as to place the chamber 3 above the furnace—which has been previously lowered by the means described—or the burner. The chamber 1 is now in the

original position of the chamber 3. The pot *l* of this chamber with the annealed and partly cooled charge is now withdrawn and replaced for a fresh pot. The position of chamber 3 in the plan view is the station 70 where the pots are exchanged. The operation is now repeated.

In my novel furnace, I may anneal 1000 to 1500 kilogrammes of goods during a period of one hour or two hours. 75

Instead of revolving annealing chambers, chambers adapted to move on a straight line may be provided. This arrangement is very suitable for plate annealing furnaces in which the goods are charged in box-shaped pots which may be suspended from a track on top of the passage. By these means, it is possible to close the passage and the boxes perfectly tightly from above. The plates are annealed bright for their entire area which was not practicable heretofore as the rims of the plates coloured blue on a strip 4 in. wide, or more which is very inconvenient with regard to galvanizing and lacquering the plates. 80

The gases from the furnace chamber *r* or the burner flow upwards along the chamber *i* which is above the furnace, being the chamber 1 in the present instance, to the chamber 2 through the flue *y'* along that chamber in downward direction, through the flue *y⁴* to the chamber 3, along that chamber in upward direction, and to the chimney flue *z*. Dampers or slides *y⁵*, *y⁶*, *y⁷*, *y⁸*, and *z'*, are provided in the respective 90 flues. The chambers are cooled at the station where the chamber 4 is shown. The heat radiated from this chamber is conducted to the flue *z* through the flue *y³* and along the chamber 3. In this manner the 100 radiating heat is utilized and, together with the waste gases, heats the goods to 300 or 400 centigrade. 105

In a furnace having 6 or 8 annealing chambers instead of four, as shown, it is possible to completely cool the goods in the furnace. Pots may be dispensed with in this manner, the tables *m* with the charge being inserted directly in the retorts and 110 treated as described. 115

I claim:

1. In an annealing furnace, in combination, an annealing chamber, a masonry lining in said chamber, a cover for the chamber and the lining, a flanged retort arranged through the cover and supported thereby and positioned in spaced relation to the lining of the chamber and snugly engaged only adjacent its top by the lining to avoid unnecessary heating, and an adjustable gas tight cover for the retort positioned above the cover for the chamber. 120

2. In an annealing furnace, in combination, a rotary plate supported at the top of said furnace, annealing chambers secured to 125 130

- said plate, means for heating said chambers, and covers secured to said chambers at the top of said furnace.
3. In an annealing furnace, in combination, a rotary plate supported at the top of said furnace, annealing chambers secured to said plate, means for heating said chambers, covers secured to said chambers at the top of said furnace, a pillar in said furnace adapted to support said plate at the centre, and a circular track in said furnace adapted to support said plate at its perimeter.
4. In an annealing furnace, in combination, a rotary plate supported at the top of said furnace, annealing chambers secured to said plate, means for heating said chambers, covers secured to said chambers at the top of said furnace, a pillar in said furnace adapted to support said plate at the centre, a circular track adapted to support said plate at its perimeter, and a ring adapted to make gas-tight connection between said plate and said track.
5. In an annealing furnace as claimed in claim 1, wherein an insert tank is provided at its upper edge with a flange for engagement with the flanged retort when the tank is arranged within the retort, and the adjustable cover extending partially into the interior of the tank and provided with an external annular flange for engagement with the flange on the tank to act as a gas tight closure for said tank.
6. In an annealing furnace as claimed in claim 1, wherein a tank is arranged within said retort and supported on the annealing chamber cover, a metal supporting table arranged in the bottom of the furnace and the adjustable cover acting to secure the tank in position and to also extend partly within the tank to act as a gas tight closure therefor, a safety valve carrying pipe arranged through the adjustable cover and opening interiorly of the tank to permit of the escape of gases formed during the heating, and another pipe arranged through the adjustable cover and having the inner part closed and the outer part opened, and a pyrometer engaged in the outer open end of the last mentioned pipe.
7. In an annealing furnace, in combination, an annealing chamber, a cover secured to said chamber at the top of said furnace, and a furnace chamber adapted to heat said annealing chamber and to be raised and lowered with regard to said heating chamber.

In testimony whereof, I have signed my name to this specification.

HEINRICH GRÜNEWALD.
